AIR COOLED SPINDLE MOUNTING FOR
MACHINE TOOLS AND THE LIKEGherald D. Scott, Worcester, Mass., assignor to
The Heald Machine Company, Worcester,
Mass., a corporation of Massachusetts

Application October 7, 1940, Serial No. 359,992

1 Claim. (Cl. 308—77)

The present invention relates to the mounting, for example, of a tool-carrying or work-carrying spindle, such as used in various types of machine tools, where, in the interests of precision operation, any expansion such as results from heat generated by the high-speed running of the spindle, must be held to a minimum.

It is recognized in all precision tooling operations that such expansion not only may have an adverse effect on the clearances for the spindle bearings, but also that the heating up of the support or housing for said bearings may cause the spindle axis to shift upwardly by an amount which, however slight, can nevertheless upset the accuracy of the tooling operation on a piece of work in the machine.

An object of the present invention is to overcome these difficulties in a simple and inexpensive manner by utilizing the spindle rotation itself as a means for rapidly dissipating the heat which is generated in the spindle mounting. Other and further objects and advantages of the invention will more fully appear from the following detailed description thereof, taken in connection with the accompanying drawing, in which

Fig. 1 is a side elevational view, partly in section and with parts broken away, of a spindle mounting embodying my invention.

Fig. 2 is an end view of the same, as seen from the line 2, 2 of Fig. 1.

Fig. 3 is a detached view, in side elevation, of an annular member associated with the other end of the assembly shown in Fig. 1.

Like reference characters refer to like parts in the different figures.

The drawing shows my invention, by way of example, as applied to the tool head or to the work head of a boring machine. Said head as shown comprises a hollow body or housing 1 which is adapted to be mounted in the usual way, either on the base or on the reciprocating table of the machine. Within the bore of housing 1 are provided suitable spaced-apart bearings, one of same being here shown as an anti-friction bearing 2 for the journaling of a high-speed spindle 3, the latter having both ends projecting beyond the housing 1; on one of said ends is secured a driving pulley 4 of special construction as hereinafter described, while the other carries a plate 5, to which is attached, in any suitable way, a boring tool, not shown, or a workholder, not shown, as the case may be.

According to my invention the body or housing 1, on its external side and top surfaces, as best shown in Fig. 2, is formed with a plurality

5 of longitudinally extending heat-radiating stationary fins or ribs 6, 6. A suitable cover or shield 7 is preferably applied to the body 1 to enclose the space 8, along the sides and the top of said body, which is occupied by said ribs or fins 6, 6.

Said space 8 containing the numerous relatively-thin fins 6, 6 of the body 1, serves as a manifold or duct for the continuous passage along 10 the body 1 of a current of cooling air, which is supplied, according to my invention, in sufficient quantity to dissipate and carry off practically all of the heat which is generated by the high-speed rotation of the spindle 3 within the body 15 or housing 1. For the generation of this air current, during all periods of operation of the spindle 3, the latter's driving pulley 4 is made to serve as an air impeller or blower; to this end, said pulley 4, inwardly of its belt-receiving surface, provides a peripheral flange or extension 9 which is formed on its inner face with a series of impeller blades 10, 10. Suitably secured by interior lugs 11, to the adjacent end of the body 1 is a substantially annular member 12 forming a 20 continuation of cover 7 and having an outwardly projecting flange 13 within which the periphery of the pulley flange 9 has a running fit,—the flanges 9 and 13 cooperating with the end of body 1 to enclose an annular space 14 wherein 25 the blades 10 are operative. The ingress of atmospheric air to said space 14 is by way of a plurality of suitable ducts or passages 15, 15 provided by the hub of the pulley 4,—it being understood that the suction created by rotation of the 30 blades 10 in said space 14 will draw in air through said ducts or passages 15, 15; all such air, under the impeller action of the blades 10, 10 is forced through the spaces between lugs 11, 11 (see Fig. 3) into the manifold or passage 8 substantially surrounding the body 1 and containing the latter's numerous fins or ribs 6, 6, said air escaping from said manifold only after passage along the full length of said body, through suitable 35 openings or outlets 16, 16 provided by a substantially annular plate 17, secured by bolts or the like to the end of the body 1, just beyond the ends of the latter's fins or ribs 6, 6.

Thus the cooling current of air set and maintained in motion by the rotation of the spindle 40 itself, is enabled by the above described construction to absorb and carry off practically all of the heat which is generated by the high-speed rotation of said spindle whereby is effectively avoided any expansion in the spindle mounting

that might cause displacement of the spindle axis from its predetermined level.

I claim:

In apparatus of the class described, a rotatable spindle, driving devices therefor, bearings in which said spindle is journaled, a body or housing containing said bearings and supporting the axis of said spindle at a predetermined level, external heat radiating fins on the top and sides of said body, a cover spaced from the top and sides of said body to form therewith a duct or manifold extending substantially the full length of said body and inclosing said fins, an annular

member at one end of said duct and having a flange substantially coextensive with said cover, said driving devices including a pulley on said spindle, said pulley making a running fit with 5 said flange, and having air openings therethrough, and fan blades on said pulley within said running fit, for drawing in air through said openings, said duct or manifold receiving said air and conducting it, in heat-exchanging relation to said fins, longitudinally of said housing for substantially the full length thereof.

GHERALD D. SCOTT.
